(57) **CLAIM**

I claim, the ornamental design for a workstation luminaire with continuous side slot, as shown and described.

DESCRIPTION

FIG. 1 is a perspective view of a workstation luminaire with continuous side slot, showing my new design; and,

FIG. 2 is a vertically enlarged partial side elevation view of the luminaire of FIG. 1, the FIG. 2 view showing a reduced horizontal extent of the claimed design relative to that shown in FIG. 1.

The workstation luminaire with continuous side slot is shown broken away to indicate non-specific length. Applicant also respectfully notes that the broken lines of FIG. 2 illustrate a boundary, and form no part of the claimed design.
